UNITED STATES PATENT OFFICE.

OSCAR HAMMERSTEIN, OF NEW YORK, N. Y.

WASH-STAND.

SPECIFICATION forming part of Letters Patent No. 223,907, dated January 27, 1880.

Application filed October 8, 1879.

To all whom it may concern:

Be it known that I, OSCAR HAMMERSTEIN, of the city, county, and State of New York, have invented an Improvement in Wash-
5 Stands, of which the following is a specification.

Figure 1 is a plan or top view of a wash-stand containing my improvement; Fig. 2, a front of the same. Figs. 3 and 4 are vertical
10 transverse sections thereof, showing the front door of the stand in different positions.

This invention has for its object to provide a folding tub for use on wash-stands having running water, or in other places. The primary
15 object is to so construct or arrange a wash-tub having a constant supply of water and a waste-pipe that a person may wash the entire body without necessarily going to the bathroom; and to this end I affix to the front door
20 of the wash-stand a tub capable of holding water, in which a person may stand and wash the body, while the usual basin in the wash-stand may serve to wash the hands and face. The door, being hinged, carries the tub forward for use when swung open. With this
25 folding tub is combined a system of water-supply and waste-pipe, as hereinafter more fully described; but, in addition to its use on a wash-stand, the said folding tub may also be
30 arranged in any other suitable position and in any other suitable connection.

The invention consists in the arrangement of hinged or movable tub, and also in its connection with the supply and with the waste-pipe, as hereinafter more fully described.

In the accompanying drawings, the letter A represents an ordinary wash-stand having a basin, B, to which water is supplied through the pipe or pipes C and faucet or faucets D,
35 and from which it is discharged through the waste-pipe E or in other suitable manner.

I desire it to be particularly understood that the construction, arrangement, or in fact even the use of the wash-stand itself does not necessarily constitute part of my invention or affect the same in any manner.

F is the door to the lower part of the stand A. This door I represent as being hinged at its lower portion, so that it may be folded
45 down upon the floor of the room, as shown in Fig. 3, or folded up into the stand, as shown

in Fig. 4; but it may be hinged at the sides, if desired. This door F carries on its inner face a tub or basin, G, which is in a proper horizontal position whenever the door is let down, as in Fig. 3, or swung open. The door is, either by a hollow telescopic hinge, H, (shown in Fig. 1,) or in other suitable manner, connected with a branch, E^x, of the waste-pipe, so that the water in the tub G may be let into the waste-pipe through the branch E^x whenever it is desired to have it escape.

As a proper connection, I prefer the telescopic hinge indicated in Fig. 1—that is to say, to have the hinge made of tubular parts, one of which, being the one which is fast to the door F, entering the other—namely, that which is fast to the frame A—so that on said hinge the door may be turned, while said hinge will also constitute a hollow channel for the escape of the water; but instead of such telescopic tubing an elastic tubular connection or any other mode of joining the folding door F to the waste-pipe may be substituted. The supply of water is furnished through a faucet or
50 faucets, I, which are placed onto or into the frame A, and connected by branches C^x with the supply-pipes C, as shown.

For the ordinary uses to which I intend to apply this invention—namely, on wash-stands—a person may wash the face and hands in the basin B in the usual manner, and may then stand in or near the tub G, or on an elevated block or footstool placed therein, or next to it, as desired, and wash the limbs and body after supplying the tub G with water, and may then discharge the water through the pipes E^x and E, fold up the tub against the frame A, and leave the wash-stand in its ordinary appearance, without having had recourse to the usual bath-tub.

It will be readily seen that this invention is useful in every dwelling, in that it permits the ordinary wash-stand to serve many uses of the bath-room, allowing the entire body to be washed with hot or cold water, as desired, thus giving the comforts of the bath-room to the occupant of every room that has a wash-stand, and the same comforts may be enjoyed wherever, in fact, this folding door be employed, whether against the wall of the room or in any other place.

I claim—

1. The door F, secured by a hinge, and provided with the tub or basin G and with the branch waste-pipe E^x, for use substantially as herein shown and described.
2. The combination of the supply pipe or pipes C^x and faucet or faucets I with the hinged door F, having the tub G on its inner face, and with the branch waste-pipe E^x, substantially as herein shown and described.
3. The folding tub G, connected with the waste-pipe E by a branch, E^x, with which it

remains in connection when said tub is folded shut, and also when folded open, substantially as herein shown and described.

4. The telescopic or hollow hinge H, combined with the folding tub G and escape-pipe E^x, substantially as herein shown and described.

OSCAR HAMMERSTEIN.
